UNITED STATES PATENT OFFICE

ELIHU D. WATT, OF PLAINFIELD, NEW JERSEY, ASSIGNOR TO RAYMOND CONCRETE FILE COMPANY, OF NEW YORK, N. Y., A CORPORATION OF NEW JERSEY

REENFORCEMENT FOR COMPOSITE PILES

Application filed September 20, 1932. Serial No. 633,965.

In the use of composite piles, which usually have lower sections of wood and upper sections of concrete, great difficulty has been encountered in effectively binding the sections together to prevent them pulling apart due to heaving of the ground.

A common method of binding the sections together is shown in Gunderson Patent No. 1,019,042, which shows vertical reenforcing rods having their lower ends bent at right angles to enter horizontal holes drilled into the upper part of the lower section, the upper end of the lower section having a portion of reduced diameter in the form of a tenon 5 embedded in the concrete of the upper section. Other expedients of somewhat similar nature have been tried, and insofar as I am aware, all of them have failed under certain conditions. For instance, when severe ground upheavals occur, the bends in the Gunderson rods straighten out and the rods pull out of their sockets in the lower pile sections.

An object of the present invention is to overcome the above described difficulty by connecting the lower ends of the vertical reenforcing rods to substantial metal bars passing horizontally through the upper ends of the lower pile section. In this arrangement, the vertical bars are subjected only to tension, while the horizontal bars are of sufficient cross section to withstand the shearing strains imposed upon them by the vertical rods. Preferably, the vertical rods are bent into U form and pass around the projecting ends of the horizontal bars.

Further and other objects and advantages will be apparent from the specification and claims, and from the accompanying drawing which illustrates what is now considered the preferred embodiment of the invention.

Fig. 1 is a view of one form of the invention partly broken away and partly in section.

Fig. 2 is a cross section on line 2-2 of Fig. 1.

Fig. 3 is a cross section on line 3-3 of Fig. 1.

In the drawing, reference numeral 10 designates a lower pile section having its upper

end in the form of a tenon 12. Passing horizontally through the tenon are bars 14, of substantial cross section with their ends projecting sufficiently to accommodate the snugly fitting U portions of the vertically extending rods 16. Staples 18 assist in holding rods 16 in position against the tenon while the concrete of the upper pile section is being poured. Usually in practice the lower pile section 10 is driven until its upper end approaches ground level, whereupon the reenforcing members are placed in position as above described, then shell 20 is mounted on section 10, leaving an annular space between the shell and tenon 12. In this space are the ends of bars 14 and the U portions of the reenforcing rods. The shell may be provided at its lower end with a welded-on stiffening ring 22 entering a groove in the lower section, as shown. Shell 20 is then filled with plastic concrete 24 which surrounds and encloses tenon 12 and the reenforcing elements so that when the concrete has set, the upper and lower pile sections form a unit effectively tied together by bars 14 and rods 16. The body 75 of the upper section may, if desired, be further reinforced by rings 26 and bars 28 or by any other suitable method.

It is to be understood that the invention is not limited to the specific embodiment herein illustrated and described, but may be used in other ways without departure from its spirit as defined by the following claims:

1. A composite pile having a lower preformed section and an upper section of concrete, said lower section extending upwardly into the lower end of said upper section, in combination with means for reenforcing the joint between said sections, said means comprising bars extending through the upper end of said lower section, and rods engaging the ends of said bars and extending upwardly into said upper pile section said bars being of sufficient cross section to prevent shearing by said rods on an upward lift of the upper section.

2. A composite pile having a lower preformed section and an upper section of concrete, said lower section extending upwardly into the lower end of said upper section, in 100

combination with means for reenforcing the joint between said sections, said means comprising a bar extending horizontally through the upper end of said lower section and projecting therefrom, and rods looped around said bar ends and extending upwardly into said upper pile section.

3. A composite pile having a lower pre-formed section and an upper section of concrete, said lower section extending upwardly into the lower end of said upper section, in combination with means for reenforcing the joint between said sections, said means comprising a bar extending horizontally through the upper end of said lower section and projecting therefrom, and U-shaped rods engaging said bar ends and having their ends extending upwardly into said upper pile section.

4. A composite pile having a lower pre-formed section and an upper section of concrete, said lower section extending upwardly into the lower end of said upper section, in combination with means for reenforcing the joint between said sections, said means comprising a bar extending through the upper end of said lower section and projecting therefrom, and rods hooked around the ends of said bar and extending upwardly, said rods and the ends of said bars being embedded in the concrete of said upper section.

5. A composite pile comprising a lower section having a tenon, an upper concrete section surrounding said tenon, in combination with means for reenforcing the joint between said sections, said means comprising bars extending horizontally through said tenon and rods bent over the ends of said bars and extending upwardly into said upper pile section.

6. A composite pile comprising a lower section having a tenon, an upper concrete section surrounding said tenon, in combination with means for reenforcing the joint between said sections, said means comprising bars extending through said tenon, rods hooked around the ends of said bars and extending upwardly into the concrete of the upper section, and means for holding the rods in engagement with the ends of the bars.

In testimony whereof I hereto affix my signature.

ELIHU D. WATT.
